3 SHEETS—SHEET 3.

UNITED STATES PATENT OFFICE.

BENJAMIN F. HARTWELL, OF REVERE, MASSACHUSETTS.

MACHINE FOR GRADING SOLES, &c.

1,368,721.

Specification of Letters Patent. Patented Feb. 15, 1921.

Application filed May 24, 1920. Serial No. 383,759.

To all whom it may concern:

Be it known that I, BENJAMIN F. HARTWELL, a citizen of the United States, residing at Revere, in the county of Suffolk and State of Massachusetts, have invented new and useful Improvements in Machines for Grading Soles, &c., of which the following is a specification.

This invention relates to machines for grading articles, such as cut soles, by determining the exact thickness of the thinnest portion thereof. A machine of this general character is illustrated in my Patent No. 1,320,227, granted October 28, 1919. In that machine a primary and a secondary feeler-bar are located in the path of movement of the stock to be graded, both of said bars being employed to bring into and put out of action mechanism which rotates and controls a rotary register wheel.

The above patent is referred to because it is part of the prior art on which the present invention is an improvement, but reference thereto will not be necessary to understand the present improvements.

The improvement relates particularly to the wheel-rotating mechanism, and has for its object to render said mechanism operative to rotate the register-wheel, by an act of the operator, instead of automatically, as heretofore.

The invention is embodied in a controlling mechanism including a manually movable member, normally in position to render said wheel-rotating mechanism inoperative, and means coöperating with said member to render the wheel-rotating mechanism operative when said member is displaced by the operator, so that the register-wheel is rotated in either direction, to indicate the thickness of the thinnest portion of a cut sole or other stock passing between the gage and feed disks.

The invention is also embodied in a movable stop which is normally held by said manually movable member in position to prevent the passage of stock between the disks, and releasable to permit such passage by a movement of the said member from its normal position.

The invention is also embodied in certain details of construction and mechanism, all as hereinafter described and pointed out in the appended claims.

Of the accompanying drawings forming a part of this specification,—

Figure 1 is a side elevation, looking from the left side, showing portions of a grading machine embodying the invention, parts being broken away, and other parts shown in section.

Fig. 2 is a fragmentary side view, showing portions of the mechanism shown by Fig. 1, in slightly different positions.

Fig. 3 is a fragmentary plan view, showing the slide, the gage disk, and the fixed table which has guides to guide the stock to the disks.

Fig. 4 is a front elevation showing portions of the machine, parts being broken away, and other parts shown in section.

Fig. 5 is a view similar to portions of Fig. 1, showing the slide moved from its normal position and the stop released.

Fig. 6 is a fragmentary side elevation, partly in section, showing a portion of the registering wheel, and portions of the wheel rotating, locking and releasing mechanisms.

Figs. 7, 8 and 9 are views corresponding respectively to Figs. 1, 2 and 4, showing a different embodiment of the invention.

The same reference characters indicate the same parts in all of the figures.

The frame or housing 12 has bearings for the main shaft 14, to which is fixed the lower or gage disk 17, having a continuous peripheral groove 18, adapted to receive a feeler-bar 20, the upper end of which normally projects from the groove at the highest portion of the disk in position to be depressed by stock moving over the disk. The upper feed disk, called the pressure disk 23, is fixed to the shaft 24, which is journaled in a bearing on the rocker arm, called the carrier 25, this being mounted to oscillate on a shaft 28 and pressed downwardly by the spring 26. The disks 17 and 23 are positively driven simultaneously in opposite directions by gearing indicated by dotted circles in Fig. 1.

The carrier 25 constitutes an element of the registering mechanism, which includes a registering-wheel 62, a portion of which is shown in Fig. 6, and means for communicating rotary movements to said wheel from the carrier 25, when the latter is raised and lowered.

As said registering mechanism may, so far

as concerns my present improvements, be of any preferred type, whether as shown in my said prior patent, or otherwise, detailed description thereof will be unnecessary herein, 5 it being sufficient to say that the registering-wheel 62 is rotated by the coöperation with said rocker-arm of wheel-rotating elements including the series of racks 97, 101, 103, and 106, Fig. 2 movable endwise in fixed 10 guides, and connected in pairs by gears, so that the racks of each pair move simultaneously in opposite directions, the gears connecting the racks 97 and 101 being the larger gear 99 (Fig. 1) meshing with the 15 rack 97, and the smaller gear 100 meshing with the rack 101. The gears connecting the racks 103 and 106 are the larger gear 104 meshing with the rack 103, and the smaller gear 105 meshing with the rack 106. 20 These connecting gears are shown conventionally by Fig. 1. Other wheel-rotating elements are the shaft 61 (Fig. 6), fixed at its upper end to a ratchet 63, and having a helical groove 80 receiving a stud 81 in a 25 vertical bar 82 which is slideable in a fixed guide. The bar 82 is reciprocated by means including an arm 98 (Fig. 6), fixed to the rack bar 97, and coöperating parts, not necessary to set forth herein.

30 The ratchet wheel 63 fixed to the register-wheel 62 is shown in Fig. 6. Said wheel 63 coöperates with a one-way locking mechanism which includes the feeler-bar 20.

Referring now to the mechanism embodying my present improvements, a fixed bed or table *a* has a slot *b* (Figs. 3 and 5) through which the upper portion of the gage disk 17 projects. *c* represents a slide which is movable horizontally in guides *d* on the 35 table *a*, and has a rack *e* on its under side. The slide is normally held by a spring *f*, in the position shown by Fig. 1. *g* represents a movable stop, formed as an arm pivoted at *h* to a fixed support and projecting 40 at a slot *i* (Fig. 5) in the slide *c*. The swinging end of the stop *g* has a recess *j* which is engaged by one end of the slot *i*, when the slide is in its normal position, as shown by Fig. 1, so that the stop is locked, 45 and held in position to prevent the stock, placed on the table *a*, from entering between the gage and pressure disks. The stop *g* is normally pressed upward by a spring *k*.

The slide rack *e* meshes with a gear segment *m*, on an arm *m'*, which is fixed to a rock-shaft *n* journaled in a fixed bearing. An arm *o* fixed to the shaft *n* is connected at its swinging end with the meeting ends of toggle links *p*, *p'*. The link *p'* is pivoted 60 to a fixed ear *q* (Fig. 1) and the link *p* is pivoted to an ear *r* on a block *s* which is vertically movable in fixed guides. The block *s* constitutes a holder or carrier for the rack-bar 106, and the said rack-bar has a 65 head *t* at its upper end, adapted to contact

with the carrier 25, as shown by Fig. 2, when the block and rack-bar are raised.

When the slide *c* is in its normal position shown by Fig. 1, the toggle formed by the links *p*, *p'* is broken, and the block *s* and 70 rack-bar 106 are depressed, so that the head *t* is separated from the carrier 25. When the slide is moved forward, as shown by Fig. 5, the toggle is straightened, or made active, and raises the said block and rack-bar to 75 bring the head *t* into contact with the carrier.

It will now be seen that when stock to be graded is placed on the table *a*, it cannot pass between the gage and pressure disks until 80 the slide *c* is pushed forward. This operation not only unlocks the stop *g*, but also raises the block *s* and rack-bar 106, and thus renders the register-wheel rotating mechanism operative, so that when the pressure 85 disk 23 and its carrier 25 are moved by the passing stock, and by variations in the thickness of the stock, the register-wheel 62 is correspondingly turned.

The stop *g* is depressed by the passing 90 stock until the latter has passed from the nip of the disks, so that the stop prevents the slide from returning to its normal position while the stock is being graded.

When the stock has passed from the disks, 95 the spring *f* returns the slide *c* to its normal position, and breaks the toggle formed by the links *p*, *p'*, so that the block *s* and rack-bar 106 drop to the position shown by Fig. 1, thus rendering the register-wheel rotating mechanism inoperative, the upper racks 97 and 101 remaining in the position in which they were left in the grading, and the register-wheel giving the correct reading. The stock is directed by a fixed guide *u* and 105 a curved spring guide *v*, said guides being at opposite sides of the path of the stock, and the spring guide *v* being fixed at one end to a rigid arm *w*.

The slide *c* may be moved by the operator's hand, applied to the outer end of the slide, or by the operator's foot, applied to a 110 treadle (not shown) connected with the slide by a rod *x*; a bell-crank lever *y*, and a link *z*.

The slide *c* constitutes a manually movable member of the controlling mechanism above described, and is normally in position to render the wheel-rotating mechanism inoperative.

Figs. 7, 8 and 9 show a simpler embodiment of the controlling mechanism, which differs from that previously described in that the manually movable member is a lever *c'* attached directly to the rock-shaft 125 *n*, said lever having two arms *c''* and *c'''*, and being formed and arranged to not only render the wheel-rotating mechanism alternately operative and inoperative, but also to constitute a stop which prevents the en- 130

trance of the stock between the disks when the lever is in its normal position, as shown by Fig. 7. A spring f' yieldingly holds the lever c' in its normal position, the lever arm c^2 being raised above the level of the nip of the disks, and preventing the entrance of stock between the disks. When the lever is manually moved to the position shown by Fig. 8, the arm c^2 is depressed and guides 5 the stock to the nip of the rolls. At the same time, the block or slide s is raised by the movement thus imparted by the lever c' to the rock shaft n , and the toggle formed by the links p , p' so that the block s and 10 rack bar 106 are raised to bring the head t into contact with the carrier 25, as shown by Fig. 8. The lever arm c^3 is provided with a handle c^4 to facilitate movement of the lever by the operator. 15

20 In each of the described embodiments of the invention, the rock-shaft n , its arm o , and the toggle formed by the links p , p' constitute means coöperating with the manually movable member to render the wheel- 25 rotating mechanism operative and inoperative. In each embodiment the controlling mechanism includes a stop such as g (Fig. 1), or c^2 (Fig. 7), which prevents the entrance of the stock between the disks when 30 the manually movable member is in its normal position.

In the operation of the machine, a piece of stock is placed on the table a at the right of the stop g (Fig. 1). The stop g will prevent the stock being passed between the disks 35 17 and 23 so as to be carried through between them toward the left in said figure until said stop is displaced. Downward movement of the stop g is normally prevented by the slide c being held in the position shown in Fig. 1 by the action of the spring f . When the slide is moved into the 40 position shown in Fig. 5, the end wall of the slot i is withdrawn from the recess j , and as 45 the stock is moved inwardly, the stop g will be rocked downward so as not to offer any obstruction to the passage of the stock between the disks 17, 23. Movement of the slide c from the position shown in Fig. 1 to 50 that shown in Fig. 5 raises the block s and rack bar 106, as hereinbefore described, and the register wheel rotating mechanism is rendered operative. The register wheel rotating mechanism will be actuated by the 55 passage of the stock between the disks 17, 23, causing a movement of the lever 25.

I claim:

1. A grading machine comprising a positively driven gage disk journaled in fixed 60 bearings, a spring-pressed carrier movable toward and from the gage disk, a positively driven pressure disk journaled in said carrier and yieldingly pressed thereby toward the gage disk, the pressure disk and carrier 65 being movable from the gage disk by inter-

posed stock, register wheel-rotating mechanism operable by movements of the carrier to rotate a register-wheel in either direction, and a controlling mechanism including a manually movable member normally in position to render said wheel-rotating mechanism inoperative, and means coöperating with said member to render said wheel-rotating mechanism operative, when said member is displaced from its normal position. 70

2. A grading machine comprising a positively driven gage disk journaled in fixed bearings, a spring-pressed carrier movable toward and from the gage disk, a positively driven pressure disk journaled in said carrier and yieldingly pressed thereby toward the gage disk, the pressure disk and carrier being movable from the gage disk by interposed stock, register wheel-rotating mechanism operable by movements of the carrier 80 to rotate a register-wheel in either direction, and a controlling mechanism including a manually movable member normally in position to render said wheel-rotating mechanism inoperative, and means coöperating with said member to render said wheel-rotating mechanism operative, when said member is displaced from its normal position, said controlling mechanism including a stop which prevents the entrance of stock 85 between the disks when said member is in its normal position, and permits such entrance when said member is displaced. 90

3. A grading machine comprising a positively driven gage disk journaled in fixed 100 bearings, a spring-pressed carrier movable toward and from the gage disk, a positively driven pressure disk journaled in said carrier and yieldingly pressed thereby toward the gage disk, the pressure disk and carrier being movable from the gage disk by interposed stock, register wheel-rotating mechanism operable by movements of the carrier to rotate a register-wheel in either 105 direction, and a controlling mechanism including a manually movable member normally in position to render said wheel-rotating mechanism inoperative, a block movable in fixed guides and carrying an element of said wheel-rotating mechanism, and connections between said block and said manually movable member, adapted to inoperatively confine the block and the element carried thereby, when said member is in its normal 110 position, and to move said block and element to an operative position, when said member is displaced. 115

4. A grading machine comprising a positively driven gage disk journaled in fixed 120 bearings, a spring-pressed carrier movable toward and from the gage disk, a positively driven pressure disk journaled in said carrier and yieldingly pressed thereby toward the gage disk, the pressure disk and carrier being movable from the gage disk by inter- 125

posed stock, register wheel-rotating mechanism operable by movements of the carrier to rotate a register-wheel in either direction, and a controlling mechanism including a manually movable member normally in position to render said wheel-rotating mechanism inoperative, a block movable in fixed guides and carrying an element of said wheel-rotating mechanism, and connections 10 between said block and said manually movable member, adapted to inoperatively confine the block and the element carried thereby, when said member is in its normal position, and to move said block and element 15 to an operative position, when said member is displaced, said connections including a toggle connected with said block and with a fixed support, and means connecting the toggle with said manually movable member 20 to break the toggle, when said member is in its normal position, and render the toggle active, when the said member is displaced.

5. A grading machine comprising a positively driven gage disk journaled in fixed 25 bearings, a spring-pressed carrier movable toward and from the gage disk, a positively driven pressure disk journaled in said carrier and yieldingly pressed thereby toward 30 the gage disk, the pressure disk and carrier being movable from the gage disk by interposed stock, register wheel-rotating mechanism operable by movements of the carrier to rotate a register-wheel in either direction, and a 35 controlling mechanism including a manually

movable slide normally in position to render said wheel-rotating mechanism inoperative, a fixed guide for said slide, means coöperating with said slide to render said wheel-rotating mechanism operative, when the 40 slide is displaced from its normal position, and a movable stop normally locked by the slide in position to prevent the entrance of stock between the disks, and releasable to permit such passage by a movement of the 45 slide from its normal position.

6. A grading machine substantially as specified by claim 5, the said stop being oscillatable and provided with a recess, and the slide being formed to engage said recess 50 and thereby lock the stop in its operative position.

7. A grading machine substantially as specified by claim 5, the said slide being provided with a rack, and the said controlling mechanism including also a rock-shaft having a toothed segmental end meshing with said rack, a toggle adapted to be made operative and inoperative by said rock-shaft, and a block connected with said toggle and 60 carrying an element of said wheel-rotating mechanism.

8. A grading machine substantially as specified by claim 5, the said stop, when displaced by the stock, being adapted to lock 65 the slide against return to its normal position.

In testimony whereof I have affixed my signature.

BENJAMIN F. HARTWELL.
